DESIGN FOR A FIRE-PLACE.

Design No. 13,448, dated November 21, 1882.

UNITED STATES PATENT OFFICE.

WILLIAM C. PEET, OF JERSEY CITY, NEW JERSEY, ASSIGNOR TO THE J. L. MOTT IRON WORKS, OF NEW YORK, N. Y.

DESIGN FOR A FIRE-PLACE.

SPECIFICATION forming part of Design No. 13,448, dated November 21, 1882.

Application filed October 17, 1882. Term of patent 7 years.

To all whom it may concern:

Be it known that I, WILLIAM C. PEET, of Jersey City, in the State of New Jersey, have invented a certain new and ornamental Design 5 for Fire-Places, of which the following is a specification..

This design is made with reference to the production of an artistic appearance similar to Egyptian architecture, as shown in the accompanying engraving.

The fender has a leaflet-wreath border, *a*, with pedestal and sphinx *b* at each of the ends, fluted columns *c*, with conical tops *d*, interwoven leaflet ornaments *e*, cornice *f*, and curved 15 ends *g*. The fire-place frame has side pieces composed of the ornamental fluted columns *h*, leaflet panels *k* and *l*, rosettes *m*, and leaflet 20 capitals *n*. The entablature is sloping at the ends and the panels ornamented with interwoven leaflet ornaments *e*, the same as on the fender. The architrave *u* and arching corner-pieces *w* are molded on the edges, and there are scroll ornaments on the surfaces, as shown. The andirons have dome-shaped heads *r*, cylindrical bodies with stem and rosette ornaments *s*, and a pyramidal top to the square 25 base *t*, ornamented as represented in the engraving. The surfaces of the metal plates at

the sides and back of the fire-place are ornamented with daisy designs, as represented. 30 I claim as my invention—

1. The design of the fender, consisting of the wreathed base *a*, sphinx *b*, columns *c*, cornice *f*, and leaflet ornaments *e*, substantially as represented.

2. The design of the side pieces of the fire-place, consisting of the fluted columns *h*, leaflet panels *k* *l*, rosettes *m*, and leaflet capitals, substantially as represented.

3. The design of the ornamental entablature, 40 consisting of the interwoven leaflet ornaments, substantially as represented.

4. The design of the andirons, consisting of the dome-shaped heads *r*, cylindrical bodies, stem and rosette ornaments *s*, and base *t*, substantially as set forth.

5. The design of the daisy ornaments on the surfaces of the fire-place sides and back, as represented.

Signed by me this 13th day of October, A. D. 50 1882.

WILLIAM C. PEET.

Witnesses:

WILLIAM G. MOTT,
GEO. T. PINCKNEY.
